UNITED STATES PATENT OFFICE.

VINA HILDEBRAND GOFF, OF IOLA, KANSAS, ASSIGNOR TO GOFF
DESIGNER COMPANY, OF IOLA, KANSAS.

ADJUSTABLE SKIRT-PATTERN.

No. 824,784.

Specification of Letters Patent.

Patented July 3, 1906.

Application filed June 15, 1905. Serial No. 265,392.

To all whom it may concern:

Be it known that I, VINA HILDEBRAND GOFF, a citizen of the United States, residing at Iola, in the county of Allen and State of Kansas, have invented a new and useful Adjustable Skirt-Pattern, of which the following is a specification.

This invention relates to adjustable skirt-patterns.

10 The object of the invention is to provide a novel form of pattern that will not only obviate the necessity of taking measurements and of making a draft therefrom, but that may be used as a designer and locator of 15 seam positions and will in use accurately denote and conform to the curves of the body as far as necessary and that will denote and accurately conform to elevations and depressions of the waist-line, according as the 20 form or style of the time may require.

With the above and other objects in view, as will appear as the nature of the invention is better understood, the same consists in the 25 novel construction and combination of parts of an adjustable skirt-pattern, as will be hereinafter fully described and claimed.

In the accompanying drawings, forming a 30 part of this specification, and in which like characters of reference indicate corresponding parts, Figure 1 is a diagrammatic view of the gore plates or patterns used in drafting a seven-gore skirt. Fig. 2 is a perspective view of the pattern applied to the representation of a human form. Fig. 3 is a detail view, 35 partly in section, of one of the belt-clamps, showing it attached to one of the templets of a gore-pattern. Fig. 4 is a collective detail view in elevation of a hook and eye used in connection with the device. Fig. 5 is a detail view of the pattern member for drafting 40 curves at the side edges of the skirt-gores. Fig. 6 is a similar view of a pattern member for drafting curves at the bottom of the skirt-gores. Fig. 7 is a view in elevation of one of 45 a set of similar bars on which are printed scales of graduated measures for determining the widths of skirt-gores at places corresponding with the belt, hip, and bottom positions on the gore-plates. Fig. 8 is a view in longitudinal section, taken on the line 8-8, Fig. 1, and looking in the direction of the arrow 50 thereon.

As each gore-plate is an exact counterpart of the others, except in the matter of length

of the distending bars of the front-gore plate 55 and in the manner of connecting the outer gores to each other at the hips, but one of the gore-plates will be specifically described, corresponding parts being indicated on the other plates by like characters of reference. 60

Referring to the drawings and to Fig. 1 thereof, 1 designates, generally, a pattern-plate for drafting one-half of the front gore of a skirt; 2, generally, a pattern-plate for drafting the first side gore of a skirt; 3, generally, a pattern-plate for drafting the second side or side back gore of a skirt; and 4, generally, a pattern-plate for drafting the back gore of a skirt. In describing the specific construction of the plate that designated 70 2 has been selected.

The structure embodies in part a narrow belt 5, of leather, tape, or any other suitable material, which passes through clamps 6 and 7, that may be made of any suitable material or shape and the detailed description of which will appear farther on. Pivotaly connected with the clamps by eyelets or rivets 8, Fig. 3, are templets 9 and 10, connecting with the lower ends of which by binding screws or posts are templets 12 and 13. In a similar manner pairs of templets 14 and 15, 75 16 and 17 are pivotaly connected by binding-screws 18, 19, 20, and 21, the lower ends of the templets 16 and 17 being pivotaly 80 connected by binding-screws 22 and 23 to the upper ends of a pair of relatively short bars 24 and 25, the said bars being slidably connected with the long side bars 26 and 27 by providing both with slots 28, binding-screws 29 and 35 serving to hold the two sets of bars assembled. 85

Curved distending-bars 30 and 31 are pivotaly connected at their lower ends by a binding-screw 32, the upper end of the bars 95 being similarly connected with the templets 12 and 13 by the binding-screws 18 and 19. A second pair of longer straight distending-bars 33 are pivotaly connected at their lower ends by binding-screws 34, the upper ends of the bars being pivotaly connected with the bars 24 and 25 by binding-screws 35, that work in the slots 28. A third pair of straight distending-bars 36 are pivotaly connected at the lower ends of the bars 26 and 27 by binding-screws 37, the ends of the bars 36 being pivotaly connected by a binding-screw 38, the bars 36 being longer than the bars 33. On 100 105

the right-hand side of the slots 28 are measuring-scales 39 of actual inches, the purpose of which will hereinafter appear.

Located at the points where the distending-bars are attached to the sides of the gore-plates are metal hooks 40, 41, and 42, and located at the same relative positions on the opposite side of the gore-plate are eyes 43, 44, and 45, the function of which will hereinafter appear.

10 The templets 9 and 10 should be made of sheet metal, and the remaining templets and bars may be made of metal, press-board, or any other tough light material suited for the 15 purpose, and the terminals of all the templets and bars should be cut on a semicircle in order to obviate the presentation of sharp corners.

In the gore-plate 1 the distending-bars 30, 31, 33, and 36 may be made of the same length 20 as the corresponding pairs in the other gore-plates or they may be made relatively shorter, as shown in Fig. 1.

The belt 5 is fastened with a buckle 46 or any other suitable fastening device. Connected 25 with the gore-plate 4 by a binding-screw 47 is a tape 48, which may be graduated and connects with the gore-plate 1 by a snap-hook 49, held combined with the gore-plate by a binding-screw 50.

30 In the plate shown in Fig. 5, 51 and 52 designate long curved templets or bars which are connected by four shorter templets 53, 54, 55, and 56, the connection being secured by means of binding-screws 57 in the same manner as the other parts of the device. The 35 plate shown in Fig. 6 consists of six curved templets 58, 59, 60, 61, 62, and 63, of which the templet 58 is the longest, the series of templets being connected by binding-screws 40 64 to permit ready pivotal movement of the members relatively to each other.

While Fig. 1 shows only four gore-plates suitable for designing and drafting a skirt of seven gores or less, as many more plates of 45 like construction may be combined with the belt as the style of the skirt demands or the size of the form permits.

In Fig. 2 there is shown one method of setting the designer preparatory to its being 50 cured as a pattern-plate for drafting. The device is suspended from the waist of a person by means of the belt, and the different gore-plates are hooked together by means of the hooks 40 42 and eyes 43 45. The plates 55 are then suitably adjusted both laterally and vertically to the form, according to the style of the skirt desired, and all of the binding-posts and belt-clamps which initially are loosened are then tightened. The plates 60 are then unhooked from each other, the belt and connecting-tape unfastened, and the device removed from the form. The gore-plates will then be rigid individually and separate from each other except at the belt, 65 when they may be used as pattern-plates for

drafting the upper members of the gores of the skirt. The side edges of the lower part of the skirt are drafted by combining the plate shown in Fig. 5, set to the desired curve upon the line drawn at the outer side of any 70 gore-plate and continuing this line along the edge of the side-drafting plate to a point indicating the desired width of the bottom of the gore.

By using the skirt-length measure three or 75 more points in the bottom curve of any gore may be located, when the pattern-plate shown in Fig. 6 may be set to this curve and the bottom edge of the gore smoothly drawn. In case of the absence of an individual to be 80 fitted the several gore-plates may be adjusted vertically by means of a scale of inches on the side of the bars 24 and 25 in accordance with variations in skirt-length measures taken at seam positions, and the lateral dimensions of 85 the plates may be ascertained by means of a series of bars containing sets of graduated scales of measures printed thereon suitable to adjusting the plates at the belt, hip, and bottom positions. These bars are identical 90 in size and alike in plan and general arrangement, and for this reason but one is shown in Fig. 7, this being the one used in adjusting the widths of the front-gore plate for a seven-gored skirt. In the plate shown in this figure, 95 65 designates the upper edge of the bar along which is placed a graduated scale of measures 66 for adjusting the width of the top of the gore-plate. Along the line 67 is placed a graduated scale 68 of measures for 100 adjusting the width of the same plate at the hip-line or at the top of the long side bars. On the lower edge 69 of the plate is a graduated scale of measures 70 for adjusting the width of the same at the bottom of the long 105 side bars. The graduated-scale measure 66 is based proportionately upon the whole belt measures. The scale 68 is based proportionately on whole hip measures, and the scale 70 is an arbitrary scale assumed to give 110 good scale form when used with hip measures corresponding to its numerical divisions. To illustrate the use of the bar 71, the following 115 example is given: If a person to be fitted measures twenty-five inches at the waist and forty inches at the hips, the top of the front-gore plate is set at "25" on scale 66, measuring from the left end of the bar, the width of the gore-plate at the top of the side bars is set at "40" on the scale 68, and the width of 120 the gore-plate at the lower end of the side bars is set at "40" on the scale 70. It is obvious that three scales similarly constructed must be used for each gore-plate adjusted, although the scales for two gores may be printed 125 on the opposite sides of the same bar, and the scales for a five-gore skirt will necessarily be different from scales for a seven-gore skirt. The blank spaces on each bar are utilized for printing necessary instructions and explana- 130

tions, especially to designate for what part of the gore each scale is intended, to what kind of a skirt the scales belong, and for which particular gore they are designed. When the 5 several gore-plates of the designer are properly adjusted vertically and laterally, as described, and the small templets are set in proper curves between the hip and belt positions, a good fit will be secured by using the 10 gore-plates as patterns, even when the device cannot be applied to the form of the individual to be fitted.

The foregoing description applies to the invention as it is generally preferred to manufacture it for ordinary purposes and for usage; but it will be obvious, first, that if it should be desired that all the templets and bars composing the several gore-plates be made of metal each may be made of narrow 15 dimensions, retaining the same length as those in the plates described; second, for children a small device may be made having all its parts of the same relative proportions as the one described, and, third, that for extremely large forms with heavy hip curves 20 or for persons unusually tall one or more templets similar to the small pivotally-attached templets corresponding to 12 and 13 in the gore-plate 2 may be added to each set 25 of templets to give the required length to the hip portions of the several gore-plates.

Having thus described the invention, what is claimed is—

1. An adjustable skirt-pattern comprising 35 a belt and a plurality of gore-defining plates, each plate embodying a pair of relatively long side bars, a pair of relatively short bars slidably combined therewith, a plurality of articulated templets connecting the last- 40 named bars with the belt, and a plurality of connected distending-bars having their terminals assembled respectively with the long side bars and with two of the templets.

2. An adjustable skirt-pattern comprising 45 a belt and a plurality of gore-defining plates, each plate embodying a pair of relatively long side bars, a pair of relatively short bars slidably combined therewith, a plurality of articulated templets connected with the last- 50 named bars, clamping elements carried by the outer templets and engaging the belt, and a plurality of connected distending-bars having their terminals assembled respectively

with the long side bars and to two of the templets.

55

3. An adjustable skirt-pattern comprising a belt and a plurality of gore-defining plates, each plate embodying a pair of relatively long side bars, a pair of relatively short bars slidably combined therewith, a plurality of 60 articulated templets connecting the last-named bar with the belt, curved distending-bars connected with two of the templets adjacent to the belt, connected straight distending-bars combined with the side bars at their 65 upper and lower terminals, and means for adjustably assembling the templets, side bars and distending-bars.

4. An adjustable skirt-pattern comprising a belt and, a plurality of gore-defining plates, 70 each embodying a pair of relatively long side bars, a pair of relatively short bars slidably combined therewith, a plurality of articulated templets connecting the last-named bars with the belt, a plurality of connected 75 distending-bars having their terminals assembled respectively with the long side bars and with two of the templets, hooks and eyes carried by the distending-bars at their point of juncture with the plate, and a measuring- 80 band having one terminal secured to one of the plates, and its other terminal adapted to engage a clamping device carried by an adjacent plate.

5. An adjustable skirt-pattern comprising 85 a belt and a plurality of gore-defining plates, each plate embodying a pair of relatively long side bars, a pair of relatively short bars provided with longitudinal graduated slots, means for slidably connecting the first- 90 named bars with the latter bars, a plurality of articulated templets connecting the short bars with the belt, a plurality of connected distending-bars having their terminals assembled respectively with the long side bars and 95 with two of the templets, means for connecting the series of plates, and means for adjustably assembling the side bars, distending-bars and templets.

In testimony that I claim the foregoing as 100 my own I have hereto affixed my signature in the presence of two witnesses.

VINA HILDEBRAND GOFF.
